UNITED STATES PATENT OFFICE.

CARL RICHARD WALLER, OF TRENTON, NEW JERSEY, ASSIGNEE TO DE LAVAL STEAM TURBINE COMPANY, OF NEW YORK, N. Y., A CORPORATION OF NEW JERSEY.

ELASTIC-FLUID TURBINE.

987,842.

Specification of Letters Patent. Patented Mar. 28, 1911.

Application filed June 10, 1909. Serial No. 501,299.

To all whom it may concern:

Be it known that I, CARL RICHARD WALLER, a subject of the King of Sweden, and a resident of Trenton, county of Mercer, and State 5 of New Jersey, have invented certain new and useful Elastic-Fluid Turbines, of which the following is a specification.

This invention relates to elastic fluid turbines, such as steam turbines, and particularly to turbines of the impact type comprising a rotating member carrying buckets, blades or vanes, against which steam or other working fluid is projected by a plurality of nozzles. It is frequently desirable to arrange to operate such turbines with working fluid from a plurality of different sources, either simultaneously or at different times, or to operate the turbine in connection with the condenser at one time and to exhaust 10 from the turbine into the air or under back pressure, at another time, or perhaps to work at times with a relatively low vacuum and at other times with a relatively high vacuum. For efficient operation, this requires a plurality of nozzles of different shapes; for 15 high efficiency requires the use of different nozzles when the turbine is working condensing from what is used when it is working non-condensing, and different nozzles 20 for use when it is operating with low pressure steam from what are used when it is operating with high pressure steam. The form of such a turbine lends itself admirably to the provision of a large number of 25 nozzles, some of which may differ in shape from others, and part or all of which may be in use at any one time.

The invention herein described comprises means whereby a large number of nozzles 40 are so arranged in connection with the rotating member, that they may be connected in groups, the nozzles of different groups receiving working fluid from different sources if desired, means being provided 45 whereby the number of nozzles in service of any group or groups may be varied as desired; and the invention further comprises an improved support for the nozzles, an improved arrangement of steam passages, and 50 various other features as more fully described hereinafter and particularly pointed out in the claims.

Steam turbines are particularly adapted 55 for operation by the exhaust steam of high pressure engines which, customarily, exhaust

into the air, the turbines in such case in effect taking the place of the low pressure cylinder of a compound, triple expansion, etc., engine, but operating with greater efficiency and being much smaller and more compact. The exhaust steam from an engine which ordinarily operates intermittently or under an extremely variable load (hoisting engines, rolling mill engines and the like) may be utilized effectively for operating a low pressure motor, by interposing 60 between the high pressure motor and the low pressure motor a steam accumulator. Various constructions of accumulators adapted for such use are known and it is not necessary for me to illustrate here any particular 65 accumulator construction. The turbine herein described is well adapted for operation simultaneously by steam derived direct from the boiler at high pressure and by exhaust 70 steam from a high pressure engine, such steam either delivered direct from such engine, or through an accumulator.

The accompanying drawings illustrate one construction of turbine embodying my invention.

In the said drawings: Figure 1 shows an end view of said turbine; Fig. 2 shows a central vertical section of the turbine on the line $x-x$ of Fig. 1; Fig. 3 shows a face view of the nozzle ring and Fig. 4 a transverse section thereof taken on the line $z-z$ of Fig. 3; Fig. 5 shows a detail section, on a larger scale, of a portion of this nozzle ring, taken on the line $a-a$ of Fig. 8, the 85 nozzle itself being omitted; Fig. 6 is a similar view showing the nozzle in place and sectioned; Fig. 7 shows an end view of the inlet end of one of the nozzles; Fig. 8 shows a detail side elevation and partial section of 90 a part of the nozzle ring; Fig. 9 shows a face view of the inner wall of the secondary chest against which wall the nozzle ring is secured, the view being a section on the line $b-b$ of Fig. 2, looking in the direction of the 95 arrow or toward the primary steam chest; Fig. 10 is a diagrammatic view illustrating various combinations in which such a turbine may be used.

Referring first to Figs. 1-4 inclusive, the 105 turbine casing as there shown comprises two sections, 1 and 2, bolted together. The rotary member or wheel 3 is mounted on a shaft 4 having stuffing boxes 5, 5. In section 1 of the casing is an annular cored 110

- chamber A constituting a steam chest, and which for the purposes of this invention is divided into a plurality of chambers by means of partitions 6 (indicated in dotted lines in Fig. 1). There may be as many of these partitions as desired, the steam chest being divided into a corresponding number of compartments. In the construction shown I have indicated three such partitions 10 dividing the steam chest into three separate compartments, 7, 8 and 9, to which working fluid may be led by pipes 10, 11 and 12, respectively. Against the inner face of section 1 of the casing a nozzle ring K is secured; and between this nozzle ring and said section 1 there is an annular secondary steam chest M (Fig. 2) divided into a plurality of compartments by means of radial ribs O (indicated in dotted lines in Fig. 1 15 and also seen in Fig. 2), which ribs fit closely against the face of the nozzle ring K, between the nozzle orifices of such ring, so dividing the secondary steam chest into a plurality of entirely separate compartments. There may be as many of these compartments as desired. In the construction shown I have indicated nine such compartments, designated respectively by reference characters, B, C, D, E, F, G, H, I, J (Fig. 20 9); and in Fig. 3 the positions of these partitions O is also indicated for convenience, in dotted lines. In the inner wall of section 1 of the turbine casing, are a plurality of openings connecting the primary steam chest 25 A to the corresponding compartments of the secondary steam chest M, said openings having valve seats adapted to receive valves 14. Each such valve is provided with a stem 18 adapted to slide axially within a stuffing 30 box 17 fitting into a screw threaded orifice in the outer wall of section 1 of the casing, such valve stem having a head 19 to which is pivoted a link 20 also pivoted to a link 22 pivoted to the stuffing box; and this link 20 35 is provided with an arm 21 which may be slotted as shown for convenient connection of a suitable operating member (not shown) thereto. It will be seen that by oscillating the arm 21 the valve 14 may be moved in 40 or out, as desired. Each of these valves 14 having such an operating device, it will be clear that any one or more of the valves may be closed or opened as desired, during the 45 operation of the turbine.

50 Referring now to the nozzle ring K, shown in detail in Figs. 3-8 inclusive, this ring has, as there shown, a plurality of recesses 23, preferably spaced at equal intervals apart, from which open slightly flaring bores 23^a adapted to receive the expansion nozzles L. These nozzles are held in place by means of threaded rings N screwing over the inner ends of the nozzles and seating against shoulders of the recesses 23. This 55 construction permits the nozzles L to be inserted into their proper openings in the nozzle ring and secured in place therein before the ring K is placed in and secured to the turbine casing; and when it is desired to remove a nozzle, or to substitute for any one 60 or more of the nozzles another nozzle or nozzles of different shape, this may be readily done by removing the ring. The sub-chambers B, C, D, E, F, G, H, I and J of the secondary steam chest may have different 65 numbers of nozzles, as may be desired to regulate the action of the turbine. In the construction shown, some of these sub-chambers have two nozzles communicating with them and others have three such nozzles. The 70 number may of course be smaller or larger as desired. Against the inner face of the nozzle ring K is a ring 24, termed a diffuser ring, and bolts passing through this diffuser ring and nozzle ring to section 1 of the turbine casing hold these two rings in place. Section 2 of the turbine casing has an annular flange 33 which, at its circumferential edge 34, is turned inwardly toward the wheel 3, the annular space between this edge 34 75 and the inner edge of the ring 24 forming a passage through which the working fluid, after acting on the buckets, blades or vanes 25 (Fig. 3), escapes to the exhaust space 26 of the turbine casing and thence to the exhaust outlet 27.

80 Fig. 10 shows diagrammatically a turbine such as illustrated in the preceding figures, having its steam chest divided into a plurality of chambers 7, 8 and 9 and having valves by which the various nozzles of each chamber may be put into action or cut off as desired. In this drawing P designates a suitable boiler or steam generator and Q a main steam pipe therefrom. R designates a high pressure engine which may be supposed to be an engine operating somewhat continuously and under somewhat uniform load, S designates an engine which may be supposed to operate intermittently or under quite a variable load, T designates a steam accumulator, U designates the turbine, V an exhaust pipe for the system, W a condenser and X a valved atmospheric outlet for the exhaust. According to the arrangement 85 shown, chamber 9 of the steam chest of the turbine is connected by a pipe 40 direct to main steam pipe Q; compartment 8 is connected to the exhaust pipe 41 of engine R and compartment 7 is connected by pipe 42 to the accumulator T itself connected to the exhaust pipe 43 of engine S. Suitable valves are provided, the function of which valves is obvious. With the steam chest of the turbine divided as shown, such turbine may be 90 operated, either simultaneously or at different times, by live high pressure steam from the boiler, by the exhaust from high pressure engine R or by the exhaust from engine S after such exhaust has passed 95

through the accumulator T by which accumulator heat is stored up during periods of active operation of engine S to be given off in steam when engine S is less active. 5 Also, by the connections shown, the whole system may be operated condensing or may exhaust into the external air. Numerals 18 designate, the stems of valves by which one or more of the nozzles of each compartment 10 of the turbine may be brought into action or shut off. It will be obvious that by means of these valves and by the subdivision of the steam chest into a plurality of compartments, the turbine is made capable of operating efficiently under a great variety of 15 different conditions; and it is also obvious that Fig. 10 illustrates only a few of the various conditions under which a turbine having its steam chest so divided may be 20 operated.

What I claim is:—

1. An elastic fluid turbine comprising in combination a turbine casing having integral walls containing a wheel chamber and 25 an annular primary steam chest, said casing comprising a partition integral with said walls, separating said wheel chamber and steam chest and provided with openings for the passage of working fluid, a nozzle 30 ring secured against said partition and provided with a plurality of nozzles adapted to project working fluid into said wheel chamber, said nozzle ring and partition having in their adjacent faces, corresponding registering recesses together forming a plurality of 35 separate secondary steam chests, said partition having in it a plurality of openings, one

for each such secondary steam chest, for the passage of working fluid from the primary steam chest to such secondary steam chest, 40 and valve means controlling the flow of working fluid from the primary steam chest to the secondary steam chest independently.

2. An elastic fluid turbine comprising in combination a casing having a wheel chamber, a detachable nozzle supporting ring, a diffuser ring, means holding said diffuser ring and nozzle ring in place in the casing and a bucket wheel adapted for rotation between the nozzle ring and diffuser ring. 45

3. In combination with an elastic fluid turbine wheel of the impact type, a casing having an annular working fluid receiving chamber, a detachable nozzle supporting ring, a plurality of nozzles in said ring, and a diffuser ring; the said wheel having its buckets interposed between said nozzle ring and said diffuser ring. 55

4. In combination with an elastic fluid turbine wheel of the impact type, a casing, 60 and in said casing, a nozzle supporting ring, a plurality of nozzles in said ring, and a diffuser ring, the said nozzle ring and diffuser ring being located on opposite sides of said wheel and forming between them an annular chamber receiving the wheel buckets. 65

In testimony whereof I have signed this specification in the presence of two subscribing witnesses.

CARL RICHARD WALLER.
